DESIGN FOR A HIGH CHAIR

Melvin Earl Melvyn, Los Angeles, Calif.

Application January 22, 1944, Serial No. 112,295

Term of patent 7 years

(Cl. D15—1)

To all whom it may concern:

Be it known that I, Melvin Earl Melvyn, a citizen of the United States, residing in the city of Los Angeles, county of Los Angeles, and State of California, have invented a new, original, and ornamental Design for a High Chair, of which the following is a specification, reference being had to the accompanying drawing, forming part thereof.

Figure 1 is a side perspective view of a high chair, showing my design; and Figure 2 is a vertical mid-sectional view on a reduced scale taken along line 2—2 of Figure 1.

I claim:

The ornamental design for a high chair, as shown.

MELVIN EARL MELVYN.
